UNITED STATES PATENT OFFICE.

HENRY RESCH, OF BAYONNE, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,370,046.

Specification of Letters Patent.

Patented Mar. 1, 1921.

Application filed May 23, 1919. Serial No. 299,166.

To all whom it may concern:

Be it known that I, HENRY RESCH, a citizen of the United States, residing in Bayonne, in the county of Hudson and State of New Jersey, have invented certain new and useful Improvements in Combined Typewriting and Computing Machines, of which the following is a specification.

This invention relates to means for yieldingly retaining index pins in certain positions on pin bars or denominational members, and is illustrated as applied to a machine of the Underwood-Hanson type, such as that disclosed in the patent to Minton, No. 1,280,065, dated September 24, 1918.

In the combined typewriting and computing machines of the type referred to, operation of the numeral keys, during passage through a computing zone, will effect a setting of index pins in accordance with the digits printed. These index pins are carried by denominational bars, one for each of the wheels, by which computation is effected, and the bar on which a pin is set corresponding to any key depression is determined by the successive movement of said pin bars from their normal positions to positions to enable pins thereon to be set by pin-setting bars operated by the numeral keys. Upon completion of a pin-setting or indexing, an operation of a general operator will effect a movement of said bars in accordance with the pins indexed thereon, and a corresponding movement of the computing wheels operated by said bars. Such machines are also adapted for performing subtraction by the complementary method, and in setting a machine for an operation of this kind, the "9" pins are depressed, and the connections between the keys and the pin-setting bars are so changed that the pin set up as a result of depression of a numeral key will have the value obtained by subtracting the value of the numeral key from "9." Provision is also made whereby the "9" pin on any of said bars will be restored to normal position upon a setting in depressed position of any other pin on the bar. In such machines, provision is made of means to yieldingly retain the indexing pins in either normal or depressed position, or in both.

According to the present invention, a resilient member, preferably in the form of a helical spring, is supported in engagement

with the pins on each of said pin bars, and co-operates with suitably formed portions of said pins to yieldingly maintain the same in positions to which they have been moved. Provision may be made of a single member having a flange to engage with certain of said pins to limit their longitudinal movements and also to prevent their rotation, and having teeth engaging the helical spring in spaces between the pins and maintaining said spring in effective position. This construction provides a simple and efficient device, adapted for economical manufacture and for ready assemblage.

Other features and advantages will hereinafter appear.

In the accompanying drawings,

Figure 1 is a diagrammatic side elevation, partly in section, of a machine of the Underwood-Hanson type, with my invention applied thereto.

Fig. 2 is a side view, with parts broken away, of a pin bar having my invention applied thereto.

Fig. 3 is a plan view of a pin bar shown in Fig. 2.

Fig. 4 is a sectional view of a pin bar, showing a pin in raised position.

Fig. 5 is a view similar to Fig. 4, showing the pin partially depressed.

Fig. 6 is a fragmentary view of part of the pin bar.

Fig. 7 is a sectional view of part of the pin bar, showing the helical spring in connection with the index pins.

Fig. 8 is a perspective view of a part of the pin cage.

Upon depression of an alphabet key 1, or a numeral key 2, motion will be transmitted by means of a key-lever 3 and bell-crank 4, to swing a type-bar 5 upwardly and rearwardly about a pivot rod 6, to bring a type 7 into engagement with a platen 8 rotatably mounted on a carriage 9. Said carriage 9 is carried by front and rear rails 10 and 11, respectively, and is urged to the left by means of the usual strap 12 and spring-drum 13.

To control the movement of the carriage under the urging of spring-drum 13, provision is made of a rach 14 secured to said carriage and engaging a pinion 15 having the usual one-way connection with an escape-wheel 16, which, in turn, is controlled for a step-by-step movement by the usual 110

fast and loose dogs 17 and 18, respectively. Actuation of said fast and loose dogs is effected by means of a universal frame 19, which is struck by a heel 20 on any of said type-bars at the end of the printing stroke.

At the rear of the machine a bar 21, carrying a tappet 22, is mounted for swinging and sliding movement on a rod 23, supported on carriage 9, and is normally held against movement along rod 23 by means of a tooth 21^a, on said bar 21, engaging in notches in a bar 24. As the carriage enters a computing zone, bar 21 will be raised into effective position by means of a roll 25 thereon engaging a zone-controlling roller 26 carried by arms 27. When bar 21 is in such raised position, tappet 22 will come into engagement successively with jacks 28 and rock the same about their pivots on the machine frame to depress links 29, and thereby rock levers 30 having engagement with transposition linkages 31. The movement of said transposition linkages will be effective through bell-crank 32 and pins 33, mounted on pin bars 34, to advance said pin bars sufficiently to bring pins 35 in position to be set by the numeral-key-operated indexing mechanism. Upon completion of the indexing of a number and actuation of the general operator, cross-bar 36, forming part of the general operator, will engage the depressed pins and advance pin bars 34, in accordance with the pins depressed, to actuate dial wheels 37.

35 In order to index numbers on said pins 35, each numeral-key-lever is provided with a pendant 38, and upon depression of a numeral key the corresponding pendant will engage an arm 39 and rock a shaft 40. The 40 rocking movement of shaft 40 will be transmitted by means of an arm 41 to a linkage 42, and cause a bar 43, forming part of said linkage, to depress the proper pin on the selected pin bar.

45 When it is desired to use the machine for subtraction, subtraction key 44 is depressed, and, by means of link 45 and arm 46, shaft 47 is rocked to withdraw a hooked latch 48 from a notch 49 in a subtraction bar 50. The subtraction bar upon such release is drawn to the rear by means of a spring 51, and a pin 52 on said subtraction bar swings an arm 53 and thereby rocks a shaft 54 from which motion is transmitted, by means of 55 arm 55, pin 56 and arm 57, to a bar 58 pivoted at its upper edge at 59 and engaging in notches 60 in said rock shaft 40. The subtraction bar in its rearward movement will also effect, through mechanism not shown, depression of a bar 61, and, incidental to the simultaneous depression of the "9" pins, the rocking of levers 62 to elevate their rearward ends. The forward movement of shafts 40, due to change in position of bar 58, will 65 cause the connections between said rock-

shafts 40 and the linkages to be changed, so that each shaft, instead of operating its usual linkage, will operate a linkage corresponding to a number obtained by subtracting the number of the rock shaft from "9", and an arm 63 on each of said shafts will be connected to a bar 64, so that actuation of any of said rock-shafts will cause depression of said bar 64. The mechanism thus far described is in general the same as that disclosed in said patent to Minton, and the subtraction mechanism is more fully disclosed in the patent to Thornton, No. 1,283,360, dated October 29, 1918.

Each of the bars 34 is provided with a pin cage 65; preferably formed separate from bar 34 and connected thereto by any suitable means. The pins 35, which are supported by said pin cage, are preferably cut away at their upper ends to provide flat surfaces 66 and opposed shoulders 67 at the ends of said surfaces. Said pins are also provided with notches 68 to coöperate with a retaining means to be described. Provision is made of a slot 69 in the pin cage, 90 and a slot 70 in the pin bar registering with slot 69, in order that a resilient device 71, preferably a closely-coiled helical spring, may be brought into engagement with all of said pins 35. A comb 72 is provided with a flange 73 which engages with surfaces 66 on all of the pins except the "9" pin, and said comb is provided with teeth 74 positioned in the spaces between said pins and which may serve as the sole means to maintain spring 71 in effective position. It should be understood that the pressure of the spring 71 against the pins to resist movement of the latter is due rather to resistance of the spring against lateral flexing than to tensioning of the spring. The forward end of lever 62 projects between the opposed shoulders 67 on the "9" pin, and serves to limit the upward and downward movement of said pin, as well as to enable lifting of 105 said pin upon depression of bar 64.

It will be seen that comb 72 by means of its flange 73 coöperates with shoulders 67 to limit the reciprocatory movement of pins 35, with the exception of the "9" pin, and 115 coöperates with surfaces 66 of these pins to prevent their rotation, and that by means of teeth 74 helical spring 71 is maintained in effective position to coöperate with notches 68.

Variations may be resorted to within the scope of the invention, and portions of the improvements may be used without others.

Having thus described my invention, I claim:

1. In a computing machine, the combination with a denominational member comprising a bar with a pin cage thereon, of pins settable in said pin cage, said bar and pin cage having a longitudinal slot exposing 130

- said pins on one side, a helical spring lying along said slot in engagement with said pins and held against longitudinal movement by engagement with the ends of said slot, said pins being formed so as to co-operate with said spring to enable said pins to be maintained in certain positions, and a device to hold said spring in said slot and to limit the movement of said pins.
2. In a computing machine, the combination with a denominational bar, of a pin cage secured to said bar, pins settable in said pin cage, means to hold said pins against rotation, a helical spring engaging said pins through a longitudinal slot in said bar and said pin cage, said pins being shaped to co-operate with said spring for determining the position of said pins, and means engaging said spring in the intervals between said pins to press said spring toward said pins.
3. In a computing machine, the combination with a denominational bar, of a pin cage secured to said bar, pins settable in said pin cage, a helical spring engaging said pins through a longitudinal slot in said bar and said pin cage, said pins being shaped to co-operate with said spring for determining the position of said pins, and a device for engaging said spring at points between said pins to press the spring toward said pins and for preventing rotation of said pins.
4. In a computing machine, the combination with a pin bar, of a plurality of round pins settable on said bar, each of said pins being cut away near its upper end to form a flat surface with opposing shoulders at the ends of said flat surface, and being provided with two adjoining notches at an intermediate portion, a comb having a flange engaging said flat surfaces to prevent rotation of said pins, and to limit their longitudinal movements, and having teeth opposite the spaces between said pins, and a coiled spring interposed between said pins and said comb to engage in said notches to hold said pins in set or unset positions.
5. In a computing machine, the combination with a pin bar, of a plurality of settable pins supported by said pin bar, said pins having opposed shoulders near their upper ends and notched formations intermediate their ends, a lever mounted on said pin bar for limited movement with respect thereto, and having one of its ends interposed between the opposed shoulders of one of said pins, a plate on said bar to engage the remaining pins between said opposed
- shoulders, and thereby limit the movement of said pins, a helical spring extending longitudinally of said bar in position to co-operate with said notched formations, and means to maintain said spring in position to co-operate with said pins, comprising members engaging said spring in spaces between said pins and on the side of the spring opposite thereto.
6. In a computing machine adapted to effect addition or subtraction by the complementary method, the combination with a computation bar, of a plurality of settable pins having depressions intermediate their ends, a lever pivoted on said computation bar and having a limited movement about its pivot, one end of said lever being connected with one of said pins so as to move therewith, thereby enabling said pin to be restored to raised position by said lever, a helical spring extending longitudinally of said bar in position to co-operate with said pins, and means to maintain said spring in position to co-operate with said pins, comprising members engaging said spring between said pins and on the side of the spring opposite to said pins.
7. In a computing machine, the combination with a computation bar, comprising a pin cage, of pins settable in said pin cage, said bar and pin cage having a longitudinal slot exposing said pins on one side, a resilient member lying along said slot in engagement with all of said members, said pins being formed so as to co-operate with said resilient member to yieldingly maintain said pins in certain positions, and means engaging said resilient member in spaces between said pins and on the side opposite said pins to maintain said resilient member in effective position.
8. In a computing machine, the combination with a computation bar, comprising a pin cage, of pins settable in said pin cage, said pins being provided with notches, a resilient member in substantially cylindrical form in engagement with all of said pins, so as to co-operate with said notches to yieldingly maintain said pins in position, and means engaging said resilient member in the spaces between said pins and on the side opposite said pins to maintain said resilient member in effective position.

HENRY RESCH.
